UNITED STATES PATENT OFFICE

2,609,487

MAGNETIC LOCK FOR MINERS' SAFETY LAMPS

Grant Wheat and Arthur G. Davis, Marlboro, Mass., assignors to Koehler Manufacturing Company, Marlboro, Mass., a corporation of Massachusetts

Application May 16, 1951, Serial No. 226,634

1 Claim. (Cl. 240—19)

1

This invention relates to miners' lamps of the type commonly referred to as "safety flame lamps" which can be ignited while in a substantially closed state through a spark igniter mechanism designed to be operated by hand from a point outside of the enclosing structure of the lamp.

In general, such a lamp includes a fount for holding a supply of naptha, or other liquid fuel; a burner of the wick type; a substantially unbreakable glass chimney encircling the wick; a woven wire mesh gauze and bonnet above the chimney; a dome top above the bonnet; and means for holding these parts together in their assembled relationship. With these elements it is customary to combine a spark igniter which has an externally located operating knob or handle, and conventional structures of this nature are objectionable owing to their being relatively cumbersome, occupying considerable space in the fount, and being difficult to remove.

The present invention deals with the problems indicated and aims to improve safety lamp structures and their spark igniter mechanism with a view to facilitating the servicing and maintenance of such devices. It is also an object of the invention to devise a structure which will be stronger, simpler, and more economical to manufacture, as well as one that will be more convenient to use. It is still further an object of the invention to provide an apparatus having outstanding safety features.

A further object of this invention is to provide a magnetic locking means for the safety lamp, the locking means being located internally of the locking rings and having means in the fount cooperating with the magnetic locking means for releasably securing the locking rings on the fount.

These and other objects and novel features will be more fully understood and appreciated from the following description of a preferred embodiment of the invention selected for purposes of illustration and shown in the accompanying drawings, in which

Fig. 1 is a vertical, sectional view, partly in elevation, illustrating the improved safety lamp construction of the invention;

Fig. 2 is a perspective view of the safety lamp fount showing the spark igniter of the invention removed therefrom;

Fig. 3 is a view somewhat similar to Fig. 2 but illustrating the igniter partly installed in the fount;

Fig. 4 is a plan view of the fount with the

igniter fully installed and shown in proper operating relationship with respect to the burner element of the lamp;

Fig. 5 is another view of the igniter mechanism shown in Figs. 1 to 4, inclusive;

Fig. 6 is a fragmentary plan view of the upper side of the fount, further illustrating the aperture through which the igniter member is inserted in installing the latter member in its proper operating position;

Fig. 7 is a cross-sectional view taken centrally through the igniter apparatus, showing the relationship of the igniter elements to one another;

Fig. 8 is an enlarged detailed elevational view of the head of the igniter;

Fig. 9 is an end elevational view of the structure shown in Fig. 8;

Fig. 10 is a view similar to Fig. 9 but illustrating a different operating position of the elements appearing therein;

Fig. 11 is a detailed view of a cam engaging member;

Fig. 12 is a detailed elevational view of the cam engaging element shown in Fig. 11 mounted on its supporting shaft; and

Fig. 13 is a detailed plan view showing parts of the magnetic locking mechanism also indicated in Fig. 1.

Referring first to Fig. 1, the lamp structure there shown comprises a fount 2 provided with an integral annular neck 3 rising from its top, and this neck is slotted at several points, some of which are shown at 4, for the passage of air therethrough. Resting on the fount inside the neck is an air admission ring 5 and it is shaped to provide a seat for the bottom of the glass chimney 6, a gasket 7 being interposed between said seat and the lower end of the chimney. On top of this chimney is another ring 8 carrying a gasket 9. The flanged lower end of the inner gauze cone 10 seats on ring 8 while the flanged cupped lower end of outer gauze cone 12 seats on the flange of inner gauze cone 10.

Surrounding these cones is a bonnet 13 resting at its lower end on a middle ring 14, and supported on the top of this bonnet is a ring 15, both of the rings 14 and 15 having numerous holes for the passage of air therethrough. At the extreme top of the lamp structure is a dome top 16 covering the upper end of the bonnet, and the usual carrying hook 17 is attached to it.

In order to secure these main portions of this lamp structure rigidly together, several retaining rods 18, in this instance five, are arranged to connect the top and bottom elements of this assembly

55

in the manner described and claimed in copending application Ser. No. 66,368, filed December 20, 1948.

As shown, each of these rods is provided with a concealed slotted head located in a countersunk hole formed in the lower side of the lock ring 20 which is screw-threaded on to the neck 3 of the fount. A series of tubes 21, each encircling a portion of one of the rods 18, is interposed between the lock ring 20 and the middle ring 14 where they space these two elements apart. The middle and top rings are spaced apart by the bonnet 13. Above the bonnet several short tubes 22 encircle the upper portions of the respective rods 18 and space the dome top 16 from the top ring 15 by a distance ample to provide ventilation.

Nuts 23 threaded on the upper ends of the rods 18 serve, when turned up, to tighten the parts of the entire bonnet and frame assembly rigidly together. Each of the nuts 23 at the upper end of the bolts is secured in a depression or socket formed in the dome top 16 which prevents the nut from rotating. Between the middle ring 14 and the adjacent flange of the outer cone 12 a spring ring or expansion ring 26 is inserted where it serves to compensate for any expansion or contraction of the parts, due to changes in temperature, and to maintain the joints in the assembly tight.

This construction simplifies the servicing of the lamp; makes it more reliable, and less likely to get out of order. It also provides a very rigid top unit convenient to handle in unscrewing the fount from it, as is necessary with the frequent refilling and other maintenance operations.

The fount is filled through an opening in its top normally closed by a screw-threaded member of the conventional type. Servicing of the lamp includes, in addition to refilling, the cleaning of the chimney 6, the bonnet and gauzes, and the inspection and cleaning of the wick and the igniter. In reassembling the parts after cleaning, the bolts 18 are checked to be sure that they are tight, and the fact that there is only a limited number of these bolts as, for example five, as compared to a much larger number, as in prior art constructions, plus the further fact that an inspection of them consists in trying them with a screw-driver at the bottom of the ring 20 in order to see if they are tight, reduces the work involved and eliminates some of the opportunities for error of inspection.

It should be noted that the heads of the bolts 18 are concealed within the ring 20 when the assembly is in its normally operative position, which protects the heads of the bolts against tampering. To this same end the enclosing tubes 21 for the rods 18, as well as the short tubes 22, are constructed with an inner diameter slightly exceeding the diameter of the enclosed rod members so that the tubular members if turned, for example by means of a wrench, or other tool, will be revolved freely around the rods without engaging these members, and therefore without producing any likelihood of indirectly threading the rods out of engagement with the nuts, either at the bottom or top of the lamp structure. It will readily be appreciated that if these tube members were not loosely contained about their respective rod portions it would be possible for an operator, while in the mine, to turn the tubes and thus unthread the rods and release the fount from the remaining portions of the lamp structure and increase the risk of an explosion.

With the shrouded bolt and tube arrangement

above described, however, and with the fount assembled, it is a simple matter to tighten the bolts after replacing the parts in the course of routine cleaning operations. As noted, each of the nuts 23 at the upper ends of the bolts is seated in a depression or socket formed in the dome top 16 which functions in the nature of a shroud to prevent the nut from being rotated.

In using safety lamps of the character described it is, in many cases, essential to provide a means for locking the lamp parts in fixed relation to one another so that these parts cannot be disengaged while the lamp is in use in the mine. To deal with this problem we have combined with the concealed locking rod structure a magnetic locking means which comes into operation when the lamp parts are brought into a fully assembled relationship. This provides a unique combination of locking means for achieving the desired result and yet affording a convenient control of the lock.

As shown in Figs. 1 and 13, we provide in the member 20 a recess 20a in which is located a locking member 20b supported for rotation about a pivot member 20c. A slot 20d extends through the inner wall of the member 20 and communicates with the opening 20a to provide a passageway through which a locking tip 20e of the locking member 20b is normally forced by means of a spring 20f.

The arrangement of the locking member is such that it is sensitive to the action of a magnet of the horse-shoe type, for example, the pole faces of which are placed on magnetizable studs at the upper side of the member 20. The magnet acts through the studs to pivot the locking member 20b in a manner well known in the art and in a direction counter-clockwise, as viewed in Fig. 13, so that the locking tip 20e is pivoted against the spring 20f and into the passageway 20d sufficiently to allow the member 20 to be freely turned about the threaded neck of the fount and thus permit removal of the latter member from the lamp.

In using the combination locking rod and magnetic locking device described, it will be understood that the fount and locking ring, when in fully threaded position, are locked in place by the tip 20e. In this condition the lamp is carried into the mine by the miner who is using it. At the end of the day, when the miner returns to the point of inspection and servicing of the lamps, he is required to deliver the lamp to the lamp man in the lamp house. The lamp man is under rigid inspection and is the only one allowed to have a magnet. He uses the magnet at this time to relieve the locking member 20a, thus permitting the removal of the fount for servicing operations.

In one preferred embodiment of the invention we combine with a safety lamp structure, as above described, a novel spark igniter mechanism in the form of a compact igniter unit which is easily installed and removed from the fount of a safety lamp and designed to be furnished as a replaceable item. This unit is of the spark type including a friction wheel or disk 50, more clearly shown in Figs. 4, 7 and 8, and provided with file cut edges working against a piece of flint or pyro metal 52 resiliently held in a tubular body 54 by means of a coiled spring 55 and a set screw 56. In the construction provided by the invention, the parts just mentioned are mounted on a cylindrical bushing 58 rigidly fastened by a screw 60 (Fig. 7) in a cylindrical holder 25. The latter member has a flat bottom surface adapted to

rest on the top plate 62 of the fount 2. Located through the plate 62 is a circular aperture 64 (Fig. 6) which is formed with a straight overhanging edge 65.

The friction wheel 50 is fixed on a shaft 66 which is eccentrically mounted for rotation in the bushing 58. One end of a spring 68 is anchored to the bushing 58 and the other end extends around, and is secured to, the shaft 66. At its inner or lower extremity the shaft 66 has mounted on it in fixed relation an eccentric cam 70 which extends radially outward and is resiliently held against a stop 72 solidly located on the bushing 58, as is better shown in Figs. 9 and 10. The cam 70 and stop 72 are arranged in spaced relation to the inner bottom surface of the holder 25, as will be noted in Fig. 7.

Supported in the fount 2 is a receiver 27 of generally tubular form which extends through the body of the fount and is sealed at opposite ends to the top and bottom plates of the latter member. It is desirable to have the top of the igniter occupy a position no higher than the top of the burner 24 when the lamp is in operation and, consequently, it is necessary in lighting the lamp to raise the friction wheel and flint assembly into such position that the spark produced by the operation of the latter will be on approximately a level with the top of the wick W, shown in Fig. 4 of the drawings.

To satisfy these conditions we have first provided a port 74 (Fig. 1) which is formed in the side of the igniter holder 25 and through which a spark from the igniter may be directed across the top of the wick when the igniter is in a raised position. To raise the igniter into proper operating relationship with the wick W, the holder 25 is constructed at its inner end with a reduced cylindrical stem which is slidably disposed through the fount plate 62 and which extends into the upper hollow end of the receiver 27. This reduced cylindrical stem comprises two bosses 28 and 29, more clearly shown in Figs. 2, 3, 5 and 7. The bosses 28 and 29 are spaced apart by an intermediate cylindrical part 30 of lesser diameter.

Cooperating with the igniter holder and its reduced cylindrical stem is a shaft 31 extending from one end of the receiver 27 through the reduced stem into the lower end of the holder 25, as noted in Fig. 7. The outer extremity of shaft 31 is threaded to receive an operating knob 33. A coiled spring 34 encircles the shaft 31, when the parts are in their operative positions, as shown in Fig. 7, and the spring abuts at its upper end against a shoulder in the receiver 27, and at its lower end against an adjacent portion of the knob 33. Consequently, this spring tends to hold the igniter in a lowered position with respect to the receiver 27. At its opposite or upper end the shaft 31 solidly supports a thin disk 76 which is received within the member 25 in a position to bear against the bottom inner surface of the latter member. The disk is provided with a cam engaging projection 78, more clearly shown in Figs. 11 and 12. The projection 78 is arranged on the outer peripheral edge of the disk in a position chosen such that it may move into engagement with the eccentric cam 70 in one location of the latter member, such as that shown in Fig. 9, for example. When the shaft 31 and disk are rotated by the knob 33 in a clockwise direction, the cam 70, together with the friction wheel shaft 66, will be rotated against the holding effect of the spring 68. As rotation continues,

the projection 78 slides outwardly along the cam 70, and at some predetermined point, such as that shown in Fig. 10, will release the cam 70 allowing it to spring back to its starting position against the stop member 72.

In operating the igniter, the knob 33 is first pushed upwardly carrying the friction wheel and flint up to the level of the wick W where they are firmly held. The knob 33 is then, at the same time, turned in a clockwise direction to rotate the friction wheel 50 through a limited arc of rotation, after which its connection with the shaft 31 is released, as above described, and the spring 68 operating through the energy stored in it by the rotation, produces a quick rotative movement of the disk in the opposite direction. This movement operates by contact of the disk with the flange 52 to produce the spark which lights the wick W. After the spark has occurred the knob is released and the spring 34 returns the knob and the igniter to their original starting positions.

During the upward movement of the knob 33 and the igniter, boss 28 slides through the hole 64 in the top plate of the fount. This boss 28 is of a shape and dimension to fit snugly within the hole 64 with a small operating clearance, and in order to accomplish this, boss 28 is formed with a flat 28a, better shown in Fig. 5. Similarly, the boss 29 is of the same peripheral shape and diameter as the boss 28 and is adapted to pass through the opening 64 at one point being formed with a flat 29a, which occurs in a plane at right angles to the plane of the flat 28a.

The boss 29 has its upper surface located at a distance from the friction wheel and flint so chosen that the latter members will lie at a correct position for directing a spark across the wick when the upper surface of the boss 29 is forced against the under surface of the plate 62 of the fount. The boss, therefore, serves as a stop to limit upward movement of the igniter during the lighting operation. It may here be observed that the igniter support 25 and the bosses 28 and 29 are all coaxial with the shaft 31, and the curved surfaces of the bosses are concentric with those of the members 25 and 30.

Occasionally it is necessary to remove the igniter from the fount, and this operation can be performed by turning the knob 33 counter-clockwise and thereby unscrewing it from the shaft 31, after which the igniter body can be lifted until the boss 29 strikes the under side of the overhanging edge 65 of the top plate of the fount. Then by giving the igniter a quarter turn in a counter-clockwise direction, the lower boss 29 is brought into the proper position to pass through the hole 35 with the flat 29a lying in register with the edge 65 of the plate. The entire igniter body can then be lifted out, as suggested in Fig. 2, and replaced with a new unit, or suitable repairs made, as are necessary.

When installing the igniter the lower boss 29 is brought into the position suggested in Fig. 2 with the flat 29a lying in register with the edge 65 of the opening 64. In this position it will be observed that the tubular member 54 projects outwardly beyond the edge of the fount neck. When thus located the boss may then be dropped down until the shoulder on the bottom of the boss 28 strikes the top plate of the fount. Then the igniter is turned in a clockwise direction into a position such as that suggested in Fig. 3, in which the upper flat 28a of boss 28 registers with the edge 65 and allows the boss 28 to be dropped

down until the member 25 seats on the top plate of the fount. In the latter position described it will be observed that the tubular member 54 has been swung around into a position such as is illustrated in Fig. 4, in which it no longer projects above the neck of the fount.

An important feature of the invention is the cooperative locking effect derived from the location of the tubular member 54 with respect to the flat 29a. As noted above, the flat 29a is so located on the boss 28 that in order for the flat to register with the overhanging edge 65, the tube 54 must project outwardly over the fount neck. By reason of this fact it will be seen that in a fully assembled position of the lamp chimney it will be impossible for the tubular member to move into a position where the igniter can be completely removed from the fount. Such a lock is important because it prevents the igniter from falling out of the fount if the lamp should be turned upside down at a time when the knob 33 has been removed.

It will also be seen that it is imperative to maintain the port 74 in proper register with the wick W, and this is provided for by the flat 28a of the boss 28 being locked against the edge 65 when the receiver 25 is in a fully seated position on the top plate of the fount, as shown in Fig. 4. Therefore, when in the position shown in Fig. 4 and in a partly raised state, such as is effected by means of the knob 33, register of the port with the wick is always maintained.

Thus it will be observed that in order to remove the igniter from the fount, it is necessary not only to remove the knob but also to produce slideable and rotative movements of predetermined degree of the igniter body in order to effect its release. It should be observed that the flat on the boss 28, as noted above, is in a plane at right angles to the axis of the tube 54 and that the flat on the lower boss 29 is also parallel to that axis and in a plane perpendicular to the first noted plane. The edge 65 in the hole 64 is also at right angles to the axis of the tube when the igniter is in its operative position. Consequently, if the operating knob should be removed, with the rest of the lamp still assembled and lighted, it would be impossible to raise the igniter far enough to free it from the hole 64. Also, the rotative movement of the igniter essential to its removal would be prevented by the igniter tube striking the inner wall of the glass chimney 6. This will be clearly seen from an inspection of Figs. 2 and 4.

The foregoing safeguards are important because if the igniter could be pushed up out of the fount merely by removing the knob, a hole would be provided through which surrounding air and gases could flow into the wick chamber inside the chimney 6 and if these gases were combustible, explosion might be produced. To further aid in understanding this danger, it should be appreciated that through the air admission ring there is always air (and gas if present) flowing into the wick chamber, a movement which is caused by the effect of the flame creating a suction. Should a mixture of air and gas reach a point at which it is explosive, an ignition may take place inside the chimney and inner gauze. This is harmless as long as there are no openings large enough for a flame to go through and reach the surrounding outside air. Actually this internal type of explosion often takes place. Its worse effect is to extinguish the flame. When this ignition inside the lamp takes place the suction is changed

to a pressure and the danger comes from the flame leaking out of the lamp, igniting gas on the outside.

A further provision made for the purpose of preventing the entrance of combustible gases into the lamp consists in providing the restriction 36 in the bore of the tubular receiver 27. That is, this bore is so restricted immediately above the spring 34 that it closely encircles the shaft 31 and prevents any appreciable leakage of gases around this operating element for the igniter and into the wick chamber.

It will be seen that the use of two spaced-apart bosses with flats at right angles to one another, in order to lock the igniter in the desired positions in the fount, is made possible by combining with these bosses an intervening reduced cylindrical portion 30, which provides for necessary rotative movement. This application is a continuation-in-part of application Ser. No. 66,368, filed December 20, 1948.

While we have herein shown and described a preferred embodiment of our invention, it is contemplated that the igniter mechanism may be utilized with various other types of lamps and the invention may be embodied in other forms without departing from the spirit or scope thereof.

We claim:

In a miner's safety lamp, a fount having an externally threaded flange set inwardly from its upper marginal edge and providing an upwardly facing annular shoulder, an aperture formed in said threaded flange, a lock ring in threaded engagement with said flange and having bolt sockets in its under face and bolt openings extending vertically from said sockets, an elongated arcuate recess formed in the bottom face of the lock ring between certain of said bolt openings, said recess being spaced inwardly from the outer face of the lock ring, an opening extending through the inner wall of the recess, a locking member including diverging arms and formed of material subject to magnetic attraction arranged in said recess, said locking member being pivotally mounted medially in said recess and one arm of said locking member terminating in an inwardly extending hook, a spring between one side of the other arm of the locking member and the adjacent wall of the recess, said spring normally urging said hook through the aperture in the side wall of the recess and into the aperture of the flange, magnetizable studs extending downwardly through the upper wall of the locking ring at opposite sides of each of said arms for association with a U-magnet, said studs being normally spaced from said arms and extending into the path of movement of the same, whereby said locking member may be swung on its pivot against said magnetizable studs to move said hook from locked to unlocked position, said lock ring being adapted to have its under face seated upon the shoulder of said fount to close said socket openings and said recess, transverse air ports formed in the bottom of said flange, an air induction ring seating on said fount inwardly of the flange, said ring being formed with lateral annular shoulders, a chimney supported on the shoulders, a gauze cone supported on the top of the chimney having an outwardly flanged bottom, a perforated ring supported upon said cone shoulder, the perforations in said ring being vertically aligned with the bolt openings in said lock ring, a hood supported on said ring outwardly of said perforations, a top ring on said hood, and a dome formed with perforations aligned with the per-

forations in said first ring and said lock ring, said dome being depressed adjacent its perforations to form nut shrouds, bolts having their heads seated in the bolt sockets in said lock ring and extending through said rings and dome, said bolts having associated nuts seated in the shrouds in said dome and adjusted by operation of their heads in said lock ring, and tubular supports of greater diameter than said bolts enclosing exposed portions of the latter, said tubular supports being supported at their lower ends upon said lock ring and having their upper ends in supporting engagement with said perforated ring.
